THERMO-COMPRESSOR

John Kirgan, Easton, Pa., assignor to Ingersoll-Rand Company, Jersey City, N. J., a corporation of New Jersey

Application April 23, 1936, Serial No. 76,075

5 Claims. (Cl. 230—103)

This invention relates to thermo-compressors, and particularly to thermo-compressors of the steam ejector type for entraining vapor and discharging it into a condenser.

5 An object of the invention is to provide an efficient and compact type of thermo-compressor adapted to permit operation to suit changing conditions in the condenser due to variations in the temperature of the water for cooling the condenser and other causes. In its preferred form the compressor includes a casing, a connection to the condenser and nozzles to permit stage compression at suitable points in said casing or connection arranged so that the quantity and pressure of steam can be regulated as may be necessary.

Another object is to provide an ejector constructed to effect drying out of the vapor as it is entrained by heating it somewhat and evaporating any particles of moisture that might be suspended therein. Thus the work of compression is facilitated.

The drawing shows a preferred embodiment of the invention, which is of course susceptible of various alterations in practice without departure from the principle of the invention.

Figure 1 is a view in section of apparatus according to this invention, and

Figure 2 is a similar view of a modification. The numeral 1 indicates a vessel from which vapor is to be extracted, this vessel having an outlet port 2 leading to the casing 3 of a thermo-compressor which discharges through a conduit 4 into a condenser 5. In practice the vessel 1 may be the evaporator of a refrigerating system, and the energizing pressure fluid of the compressor may be steam or any other suitable medium. The condenser may be cooled by water or any other agent which may be admitted to the condenser, either in the form of spray or caused to flow through cooling pipes which are not shown herein. The casing 3 carries at one end a steam chest or header 6 from which nozzles project into said casing, the ends of these nozzles being received and enveloped by the enlarged inner extremity 8 of the conduit 4, which is at the other end of the casing but projects far enough into the casing 3 for this purpose. The nozzles 7 receive steam from a supply pipe 9 and when the ejector is in action the entraining effect of the fluid directed by the nozzles 7 into the conduit 4 causes vapor to flow out of the evaporator 1 through the port 2 and into the conduit 4.

The steam chest 6 also carries a central flue or 55 extension member 10 which projects centrally

therefrom and extends into the conduit 4. This flue 10 is long enough to pass entirely through the casing 3 and into a part of the conduit 4 that is outside of this casing. The conduit 4 and flue 10 provide an annular passage 11 which receives nozzles 7. Preferably the conduit 4 is convergently constructed between the inlet end 8 and the throat section 14. The annular passage between the flue and conduit then acts as a venturi, having a constantly decreasing area at the section 11, a throat section 23 of constant area, and an expanding chamber in the section 24 prior to the entrance to the second throat section 14, and the annular passage thereby improves the compression characteristic of the nozzles 7. The end of the flue 10 is closed but carries a number of additional nozzles 12. This flue or extension 10 receives steam from a pipe 13 to be discharged from the nozzles 12. Just beyond these nozzles the conduit 4 has a contracting portion 18 leading to a reduced section 14 and beyond this section 14 the section 15 of the conduit expands up to the point where it is connected to the condenser 5. The steam pipes 9 and 13 contain shut-off valves which can be manipulated by outside knobs 16 and 17 respectively.

In operation the annular space 11 forms a primary passage through which the steam from the nozzles 7 and the vapor from the evaporator 1 are transmitted. The pressure and velocity of the vapor is increased in this passage. So long as the temperature of the water for cooling the condenser does not become too warm, the nozzles 7 will ordinarily be sufficient. If, however, the cooling water of the condenser undergoes too much rise in temperature the nozzles 12 are also brought into action. When these nozzles are used the flue 10 serves to carry steam from the pipe 13 thereto. These nozzles act upon the steam and vapor in the passage 11 and compress them further, in the secondary compression space 19 enclosed by the constricted section 18 of the conduit 4, into the small section or neck 14 whence they issue into the diffusing section 15 of this conduit and are impelled into the condenser 5. Thus the thermo-compressor can work just as advantageously when the condenser is warmer because, as the water becomes warmer and the pressure in the condenser rises, the nozzles 12 enable the increased pressure in the condenser to be overcome and the mixture of steam and vapor delivered as before to the condenser to be liquefied. The pipe 13 delivers into the flue 10 and the steam chest 6 has an annular chamber 20 surrounding the flue 10 to

receive steam for the nozzles 7. When the water for the condenser is cooler the nozzles 12 may be kept inoperative to save steam because then the pressure in the condenser will be lower and 5 the steam from the nozzles 7 will be sufficient to serve the purpose.

The action of the ejector is further assisted by the temperature of the central flue 10 which acts as a heating element to vaporize any moisture that may be present in the vapors as they pass through the passage 11, especially when the nozzles 12 are in action. The heating effect permits an increase in velocity of vapor flow in the passage 11 and through the throat section 23 thereby enabling the nozzles 7 to draw more vapor through the inlet 2. Steam at any suitable pressure will of course be used to energize the nozzles 7 and 12.

This nozzle arrangement is very efficient and 20 well adapted to remove vapor from the evaporator 1 as the pressure in the condenser 5 rises or falls due to changes in the cooling water thereof or in the output of the system. The compressor thus provides reserve capacity so that 25 as the load rises, a greater refrigerating effect can be obtained by the use of more steam with the nozzles 12, and when the demand for refrigeration drops, less steam can be provided by shutting off the steam pipe 13. Hence the compressor can operate as conditions demand whether the water for cooling the condenser is warm or cold and whether the load on the system be full or part load.

It is to be noted that the nozzles 7 will take 35 care of ordinary loads and that the nozzles 12 are well adapted to enable the compressor to work with higher loads because they are placed adjacent the neck or throat 14 where the compression is greatest and the resistance to the flow 40 is strongest.

The header 6 fits into an opening 21 in the casing 3 and has a peripheral flange 22 to engage the casing 3 around said opening to enable the header or chest to be secured in any suitable 45 way.

In Figure 2 the steam chest 6 has a tapering extension 10^a with no nozzles at its inner end. This extension is hollow and a pipe 18 serves to deliver steam to the extension. The nozzles 50 7 are positioned around the member 10^a and steam is conveyed thereto by a pipe 9 through an annular chamber around the extension 10^a in the steam chest 6. In operation the steam filling this extension 10^a keeps it warm and any

moisture carried by the vapor which enters the casing 3 through the opening 2 and deposits on this member 10^a is evaporated.

I claim:

1. A thermo-compressor having a casing, a discharge conduit having a throat therein, nozzles in the casing to discharge a pressure fluid into the conduit, means to deliver pressure fluid to the nozzles, a heating element extending into the conduit beyond said throat to impart heat to the media passing through said throat, and means for heating the element. 5 10

2. A thermo-compressor having a casing, a discharge conduit having two throats therein, nozzles in the casing to discharge a pressure fluid into the conduit, means to deliver pressure fluid to the nozzles, a heating element extending into the conduit beyond the first throat to a point adjacent the second throat, additional nozzles positioned between the throats for discharging additional pressure fluid into the conduit, and means for heating the element to enable the element to heat the media in the conduit. 15 20

3. A thermo-compressor having a casing, a discharge conduit having a throat therein, a hollow heating element extending into the conduit through and beyond the throat, nozzles to discharge a pressure fluid into the conduit and throat, means to deliver pressure fluid to the nozzles, additional nozzles positioned beyond the throat and leading from the element to the conduit, and separate means to deliver pressure fluid through the element to the last said nozzles to thereby impart heat to said element. 25 30

4. In a thermo-compressor, a casing, a discharge conduit associated with the casing, nozzles in the casing to discharge a pressure fluid into the conduit, means to deliver pressure fluid to the nozzles, a heating element within the conduit defining a throat section in the conduit 40 and adapted to heat media in the throat section, and means to heat the element. 35 40

5. A thermo-compressor having a casing, a discharge conduit having a throat therein associated with the casing, nozzles in the casing to discharge a pressure fluid into the conduit, means to deliver pressure fluid to the nozzles, a heating element extending into the conduit through said throat to impart heat to the media in the conduit, additional nozzles positioned beyond said throat for delivering additional pressure fluid to the conduit, and means to deliver pressure fluid to the heating element to impart heat thereto. 45 50

JOHN KIRGAN.
